US0D1049441S

(12) **United States Design Patent** (10) **Patent No.:** **US D1,049,441 S**
(45) **Date of Patent:** **** Oct. 29, 2024**

(54) **VEHICLE LIGHT WITH SENSOR**

(71) Applicant: **Daimler Truck North America LLC**,
Portland, OR (US)

(72) Inventors: **Austin Cox**, Portland, OR (US); **Steven Powell**, Beaverton, OR (US); **Anthony Morgan**, Vancouver, WA (US); **Jeffrey Cotner**, Portland, OR (US); **Daniel Kunzelmann**, Portland, OR (US); **Mauricio Cavalheiro**, Portland, OR (US)

(73) Assignee: **Daimler Truck North America LLC**,
Portland, OR (US)

(**) Term: **15 Years**

(21) Appl. No.: **29/835,036**

(22) Filed: **Apr. 15, 2022**

(51) **LOC (14) Cl.** **26-06**

(52) **U.S. Cl.**

(57) **CLAIM**

The ornamental design for a vehicle light with sensor as shown and described.

DESCRIPTION

FIG. 1 is a perspective view of a vehicle light with sensor showing our new design.

FIG. 2 is a side view thereof.

FIG. 3 is a front view thereof; and,

FIG. 4 is an enlarged view of the portion identified in FIG. 1.

The dot-dash lines depict boundaries of the claimed design. The even dash lines show environmental structures and form no part of the claimed design.

1 Claim, 4 Drawing Sheets
